UNITED STATES PATENT OFFICE.

JAMES THOMAS EDWARDS, OF LONDON, ENGLAND.

BRUSH FOR USE IN CLEANING TEST-TUBES, BOTTLES, OR THE LIKE.

1,332,034.

Specification of Letters Patent. Patented Feb. 24, 1920.

Application filed September 25, 1919. Serial No. 326,375.

To all whom it may concern:

Be it known that I, JAMES THOMAS EDWARDS, a subject of the King of Great Britain and Ireland, residing at 8 North Villas, 5 Camden Square, London, N. W. 1, England, have invented a new and useful Improvement in Brushes for Use in Cleaning Test-Tubes, Bottles, or the like, of which the following is a specification.

10 This invention has reference to improvements in and relating to rotary brushes of the type having a hollow core from which bristles project and adapted to be mounted on the end of a rotatable spindle for the 15 purpose of being inserted into a test tube, bottle or the like and rotated therein to clean same with the coöperation of a washing liquid introduced through the hollow core; and the outstanding feature of my invention 20 consists in arranging the "bristles" (in which expression I include wire or other imitation bristles) so that they project from the core tangentially to a circle concentric with the axis of rotation of the brush, instead of projecting radially as usual heretofore. A further feature consists in the provision of a cushioning device on the end of the said core.

I have illustrated my invention in the accompanying drawing, in which:

Figure 1 shows a brush having bristles which project tangentially at opposite sides of a hollow core, and on the end of which core a cushioning device is fitted;

35 Fig. 2 shows on a larger scale a transverse section of the said brush; and

Fig. 3 shows, also on a larger scale, details hereinafter described.

The brush illustrated in Fig. 1 has a hollow core A made of two similar trough-shaped or semi-tubular parts a, a' made of sheet metal, shown separately in Fig. 3, each of which parts has one longitudinal margin bent back outward to form a channel or 45 groove a². Bristles B, of a length sufficient to project the required distance from the core after they have been folded on themselves and mounted on the core, are arranged side by side and folded upon themselves over a length of fine wire b so that 50 the two limbs of each folded bristle project

at right angles to the said wire, and this wire with the bristles folded thereon is placed in the aforesaid channel a². The lip of the channel is then pressed down to clamp 55 the wire and the bristles securely in position in the groove, and the two parts a, a' are brought together, face to face—so that the two rows of bristles project at opposite sides—and secured to each other by soldering together their contacting edges to form 60 the hollow core as shown in Fig. 2. It will be obvious that this construction may be varied in many ways.

In order to obviate the risk of breaking a 65 fragile test tube if it were pressed against the rotating metal core of the brush, I provide the end of the said core with a cushioning device adapted to act as a brush on the bottom of the tube. A piece of sponge 70 or the like secured by a fine wire on the end of the core would serve the purpose but it would wear out quickly, and I have accordingly devised the more durable cushioning device shown in Fig. 1 consisting of a rubber or like button C which may be formed 75 with a number of small peripheral projections and is carried on the brush core by means of spring arms d embedded in the button and engaged in holes or slots in the 80 core. The button is held yieldingly up to the end of the said core, a cavity being formed centrally in the button to receive a small coil spring e between which and the end of the core a washer f is interposed. 85

What I claim as my invention and desire to secure by Letters Patent is:

A rotary brush consisting of a hollow core formed of two similar trough-shaped lengths of sheet metal each of which has one 90 longitudinal margin bent back outward to form a channel, and bristles folded upon themselves over a length of thin wire and clamped together with the said wire in the said channels with the two ends of each 95 bristle projecting therefrom, the said trough shaped members being secured to each other face to face so that the two rows of bristles project at opposite sides and tangentially to the said core.

JAMES THOMAS EDWARDS.
